UNITED STATES PATENT OFFICE.

HERBERT S. PULLMAN, OF MERIDEN, CONNECTICUT.

SHOE-FASTENING.

SPECIFICATION forming part of Letters Patent No. 481,638, dated August 30, 1892.

Application filed October 15, 1890. Serial No. 368,225. (No model.)

To all whom it may concern:

Be it known that I, HERBERT S. PULLMAN, of Meriden, county of New Haven, and State of Connecticut, have invented new and useful 5 Improvements in Shoe-Clasps; and I do hereby declare the following, when taken in connection with accompanying drawings and the letters of reference marked thereon, to be a full, clear, and exact description of the same, 10 whereby any one skilled in the art can make and use the same, and which said drawings constitute part of this specification, and represent, in—

Figure 1, a perspective view; Fig. 2, a longitudinal central section; Fig. 3, a tongue-blank; Fig. 4, a base-plate blank; Fig. 5, an elevation of tongue when formed; and Fig. 6, a longitudinal section of base-plate, showing pintle-bearing.

20 My invention relates to the class of shoe clasps and buckles that are composed of two or more parts attached to opposite edges and adapted to engage each other for holding together a shoe, coat, or like article of wearing-apparel. In such structures it is common to 25 use a tongue on the one part and a plate with a series of openings on the opposite part of a shoe or other article, the several holes in the catch-plate or take-up being for the purpose of adjustment. In using such a clasp on a 30 shoe the catch-plate is fastened to one quarter of the shoe by a strap looped through an opening at one end of the plate, leaving the other openings for the reception of the tongue 35 of the buckle member. The clasp or buckle is fastened to the other quarter of the shoe in like manner, and by inserting the tongue into one of the openings of the catch-plate and then closing the tongue into the proper position it forms a substantial and easily-manipulated locking device.

It is the object of my invention to provide a simple, safe, easily-manipulated, and artistic clasp or buckle to be used in connection 45 with the ordinary style of catch-plate.

To this end my improvement consists of a base-plate having a solid integral bar lying over and contiguous to the straight portion of the tongue when closed, pintle-bearings struck 50 down in the lower portion of the base-plate, the base-plate bent upon itself, thereby forming a spring, which rests upon the tongue mem-

ber, and the tongue slightly extending beyond the line of the pintles at their outer portions; and it further consists in details of these parts 55 and their combination in a shoe clasp or buckle, as more particularly hereinafter described, and pointed out in the claim.

In the accompanying drawings, the letter *a* denotes the shoe-clasp as a whole; *b*, the blank 60 of which the tongue is formed; *b'*, the slightly-curved end of the tongue, and *b'' b''* the pintles; *c*, the base-plate blank; *d d*, the pintle-bearings struck transversely across the base-plate; *e*, the solid integral bar lying upon and 65 contiguous to the straight portion of the tongue when closed; *f*, the portion of the base-plate which is folded upon the other portion and terminating at *f'*; *g*, the straight portion of the tongue when formed; *h h*, the place of 70 bending or folding the base-plate; *k*, a longitudinal section of base-plate before folding, and *m m'* substantially the shape of the perforations in the base-plate before folding.

By reference to the accompanying drawings 75 it will readily be seen that the perforations *m* and *m'*, when the base-plate is folded or bent upon itself, will form one oblong hole for the purpose of attaching to the shoe or other article, as shown in Fig. 1. The object of the 80 shape of the perforation *m'* is that it permits the straight portion of the tongue *g* to pass through the lower portion of the base-plate and rest against the bar *f* when the tongue is 85 swung open on its pintles *b'' b''*, the pintles resting in the pintle-bearings *d d*, the bar *f* forming a stop to prevent too much motion of the tongue. The bar *e* serves the double 90 purpose of preventing transverse expansion of the pintle-bearings *d d* and also forms a stop for the tongue when closed.

By reference to Fig. 3 it will be seen that the tongue at *b'* projects beyond the line of the pintles *b'' b''*. When the base-plate is folded or bent upon itself, the bar *f* rests directly over the pintle-bearings *d d*, and the 95 pintles *b'' b''* of the tongue being in the pintle-bearings, it will be seen that in attempting to swing the tongue in either direction the projection *b'* will come into contact with the 100 bar *f*, which imparts a spring motion to the tongue. The pintle-bearings *d d* are of substantially the same depth below the dividing-line of the base-plate as the thickness of the

metal of which the tongue is formed. The bar *e* is struck up above the dividing-line of the base-plate substantially as far as the thickness of the base-plate metal, so that when the base-plate is completed the top portion presents a substantially-smooth surface, as best shown in Fig. 1, and a substantially-straight line from end to end, as in Fig. 2.

The construction above described is that preferred by me; but I do not limit myself to making the base-plate of a single piece, as it is evident that it could be made of two or more pieces clamped or otherwise fastened together.

I claim as my invention—
15 In a spring clasp or buckle, the combination

of a hook-shaped tongue or lever, a base of two thicknesses of metal lying contiguous, the lower plate of said base having an opening for the lever, pintle-bearings, and the solid integral bar *e*, struck up to rest in a plane with the top plate and forward of the pintle-bearings and the top plate of said base terminating at its front edge approximately at the rear edge of the bar of the lower plate, all as described and shown, and for the purpose set forth.

HERBERT S. PULLMAN.
